UNITED STATES PATENT OFFICE.

HERMANN BIEGER, OF PHILADELPHIA, PENNSYLVANIA.

STRAIGHT-KNITTING MACHINE.

SPECIFICATION forming part of Letters Patent No. 414,006, dated October 29, 1889.

Application filed October 17, 1888. Serial No. 288,404. (No model.)

To all whom it may concern:

Be it known that I, HERMANN BIEGER, a subject of the Emperor of Germany, residing in the city and county of Philadelphia, State 5 of Pennsylvania, have invented a new and useful Improvement in Straight-Knitting Machines, which improvement is fully set forth in the following specification and accompanying drawings.

10 My invention relates to improvements in knitting-machines, and has especial reference to improvements in knitting-machines in which the Jacquard cards are used for controlling the action of the needles.

15 The object of the invention is to provide a simple, inexpensive, and efficient mechanism which will in conjunction with the operating mechanism of the Jacquard cards produce fancy designs or patterns.

20 To attain the desired object the invention consists in the mechanism illustrated, described, and specifically claimed.

Figure 1 represents a vertical sectional view of a knitting-machine constructed in accordance with and embodying my invention. Fig. 2 represents an end elevation thereof, illustrating the driving mechanism and mechanism for operating the card-rollers. Fig. 3 represents a top plan view of one end of the 30 machine. Fig. 4 represents a top plan view of a portion of the needle-bed, cams, and parts of the machine operating therewith. Fig. 5 represents a plan view of one of the cards which form the Jacquard pattern-chain.

35 Similar numerals of reference indicate corresponding parts in the several figures.

Referring to the drawings, the numeral 1 designates the frame-work of the machine; 2, the driving-shaft mounted therein; 3, the operating-crank on said shaft; 4, the sliding carriage connected with the operating-crank; 5, the upper cams, and 6 designates the lower cam carried by the carriage or cam-box.

7 designates the needles, and 8 the needle-bed in which said needles are located.

The parts mentioned are of well-known construction and operate in conjunction with my improvements.

50 In the needle passages or grooves of the needle-bed, and in line with the needles, are arranged bits 9, provided at their upper ends with upright feet 10, adjacent to and oppo-

site the similar shaped feet of the lower ends of the needles. The feet on the needles and feet 10 are both adapted to be operated upon 55 by the cams, as will presently appear. Beneath and resting against the bits 9 are bits 11, provided at their upper ends with down-turned feet 12, which are arranged in slots, passages, or openings 13 in the needle-bed. Secured to each section of the carriage 4 is a flat spring 14, having on its ends the plates or blocks 15, adapted to bear on the shanks of the bits 9, and therefore on the bits 11, so as to reliably depress the same. The slides 60 16, which are secured to the carriage adjacent to the springs 14 and cam 6, are adapted to move or slide on the rails 17, supported on the needle-bed, and bear against the plates 18, having elongated slots 19 therein, through which 65 pass the screws 17^x on the rails 17. It will be seen that the bars or plates 18 are capable of an up-and-down movement by means of the slots and are inclined at their ends 20, as shown. Fulcrumed on the bar or rod 23, below the lower end of the needle-bed 8, are the levers 22, one limb of each of which is curved so as to have its outer or upper end 21 bearing against the lower edge of the bar 18, the other limb of the lever being connected to the 70 card-roller 24. The rollers are of a peculiar shape to allow the cards to revolve thereon—that is, are of octagonal shape—and are provided with cavities or recesses 25, to receive the downturned feet 12 of the springs 11. 75

26 designates the belt or chain formed of the cards 27, passing over the rollers 24 and over guide-rollers 28, and the cards are provided with openings or apertures 29, which are adapted to register with the recesses 25 90 of the rollers, and which allow the passage of the feet 12 on the spring 11. The openings or apertures are arranged on the cards in the desired manner, in order to produce the proper pattern or design.

95 30 designates ratchet-wheels carried by the shafts of the rollers 24, and the said ratchet-wheels are adapted to move up and down with the rollers 24, the shafts moving in the guides or ways 31, secured to the frame. The 100 dogs or pawls 32, which engage the ratchet-wheels 30, are pivoted to levers 32^a, mounted on the frame 1 of the machine and having their lower ends kept in engagement by

springs 32^b with the cams 33, mounted on the driving-shaft 2, as is clearly shown in Fig. 2. From this construction it is evident that when the rollers move down from the needle-bed 5 the cams operate the spring-dogs and rotate the ratchet-wheels one tooth on the rollers the distance of one card to produce a new card. From the foregoing description, taken in connection with the drawings, the operation 10 will be readily understood, and, briefly stated, is as follows: It will be seen that when the carriage 4 is moved so that the slides 16 thereon are brought in contact with and bear against the plates or bars 18 the outer ends of 15 the levers 21, which are in contact with said bars, are pressed downward, thereby elevating the ends of the levers carrying the rollers 24, and thus bringing a card on said rollers in contact with the needle-bed 8 at the slot 20 13 thereof. As the carriage is moved across the face of the needle-bed the openings in the card of the pattern-chain permit the foot 12 of the bit 11 to drop into the recess of the roller, thus lowering the bit 9, which bit is 25 reliably pressed down by the spring 14 and plate 15, so that the foot 10 is below the cam 6. In this case the needle only is moved by the cam. If there is no opening in the 30 card under the foot 12, the bits 9 and 11 are not depressed and the foot 10 is engaged by the cam 6, so that it operates or raises the needle to the position marked *a*, Fig. 4, where the old loop on the needle is allowed to go over the latch and the needle takes 35 a new thread, forming a stitch in its next downward movement. When the foot 12 drops into an opening in the card and recess in the roller, the needle is raised to the position shown as *b*, Fig. 4, where the hook of the 40 needle engages in the thread and the old loop remaining on the latch, forming what is known as a "tuck-stitch." The difference in the heights to which the needles are raised in 45 the two positions is the thickness of the foot 10 of the bit 9. It will be noticed that before the cam 6 comes in contact with the foot of the bit 9 the block 15, which is in front of the cam, will depress the said bit if there is an 50 opening in the pattern-chain for the foot of its coinciding bit 11. If there is no opening, then the carriage with the cam will be raised so that the cam will pass over the foot of the said bit 9, as shown at the right hand, Fig. 1, and not raise the said bit 9, the needle 55 only being raised. The inclined or beveled corners on the upper edges of the bars 18 and on the lower corners of the slides 16 permit the contact and movement of said parts one on the other without liability of blocking, 60 and also prevent any abruptness of action as well as lessen the tendency of breaking of the parts. As the slide 16 passes or moves off the bar 18 the latter is raised by the pressure of the levers 22, due to the weight of 65 the rollers 24, the said rollers at the same time being lowered, so that they may be rotated by means of the pawls 32 and ratchet-

wheels 30, operating the shaft 2 of the said rollers. It will be noticed that cams 5 restore the needles to their original positions.

It will thus be seen that I provide a machine which will knit different characters of designs or patterns in a perfect manner.

The many advantages of my machine will be readily understood by all skilled in the art, and hence need no further comment herein.

Having thus described my invention, what I claim as new, and desire to secure by Letters Patent, is—

1. In a knitting-machine, the combination of a cam-carriage, a slide secured to said carriage, a bar operated upon by the slide, levers having their outer ends supporting said bar, and a roller carried by said levers, substantially as described.

2. In a knitting-machine, the combination of the needle-bed, the carriage carrying the cams, the bits having the feet adapted to be operated upon by said cams, the needles adapted to be in contact with said bits, the slide carried by the carriage, the bars or plates having the elongated slots, the levers abutting against said bars or plates, the rollers carried by said levers, and the bits having the feet adapted to engage the openings in the cards, all arranged and operating in the manner and for the purpose described.

3. A needle-bed with needle-grooves having slots therein, needles having feet, bits with feet projecting into said slots, bits resting on said first-named bits and having feet at their upper ends, said last-named bits adapted to move in the needle-grooves, a carriage provided with a cam adapted to engage said needles and said last-named bits, and means to raise the feet of the first-named bits, said parts being combined substantially as and for the purpose set forth.

4. A needle-bed with needle-grooves having slots therein, needles in said grooves, lower bits with downwardly-projecting feet in said slots, upper bits with upwardly-projecting feet in said needle-grooves, a spring-plate having blocks thereon adapted to depress said bits, a carriage provided with a cam for engaging said needles and upper bits, and means to raise the feet of the first-named bits, said parts being combined substantially as and for the purpose set forth.

5. A needle-bed with needle-grooves having slots therein, needles having upwardly-projecting feet, bits having feet in said slots, bits on said first-named bits and having feet at their upper ends, a carriage provided with a cam adapted to engage said needles and last-named bits, and a roller adapted to carry a Jacquard pattern-chain, and means for raising, lowering, and rotating, said parts being combined substantially as described.

6. A needle-bed with needle-grooves having slots therein, needles in said grooves, bits having feet projecting in said slots, bits having upwardly-turned feet, a carriage provided

with a cam adapted to raise said needles, bits having upwardly-turned feet, a slide secured to said carriage, a rail for said slides, a bar secured loosely to the needle-bed, and a shaft 5 carrying rocking levers having their upper ends bearing against said bar and the other ends carrying a roller which is adapted to carry a Jacquard pattern-chain, said parts being combined substantially as and for the purpose set forth.

7. A knitting-machine having a grooved needle-bed with the slots 13 therein, needles in said grooves, the bits 11, with feet 12 projecting in said slots, the bits 9, resting on said 15 bits 11 and provided with feet 10, the carriage

4, with cam 6, spring 14, and blocks 15, connected therewith, the slide 16, the longitudinal bar 18, having slots extending transversely thereof and secured to the carriage-bed, the shaft 23, with levers 22 thereon, the upper 20 end 21 of said levers bearing against said bar 18, and roller 24, on the other ends of said levers, having recesses 25 and adapted to carry a Jacquard pattern-chain, said parts being combined substantially as and for the purpose set forth.
